In Italy October 25, 1932

7 Claims. (Cl. 117—23)

This invention relates to devices for twisting and doubling cotton and like rovings, slivers, yarn, strand, cable and like textile filamentary material, all hereinafter referred to for brevity 5 by the common denomination "yarn".

A number of forms of combined twisting and doubling units for yarn are known, wherein a plurality of yarns fed each from a supply bobbin, cop, cheese or the like carried in the unit, 10 first receive a twist and are then doubled or brought together in the form of a composite strand which itself then receives a twist.

The present invention relates to twisting units 15 of this particular class (hereinafter referred to as twisting units of the class specified) and comprises an improved form of unit characterized by enhanced simplicity of construction and efficiency of operation.

The invention involves the use of the well-known principle of twisting yarn, according to 20 which the yarn is drawn off a bobbin, cop, cheese or the like (hereinafter referred to for brevity simply as a bobbin) on to a rotary flier disposed opposite one end of the bobbin and coaxially 25 therewith, being received upon this flier at a point thereon (hereinafter referred to as the leading-on point) at or near the rotational axis of the flier and being guided upon the flier to a point thereon at or near the radially outer extremity of the flier, from whence the yarn, as the 30 flier rotates, balloons around the bobbin to the radially outer extremity of a second yarn guide disposed coaxially with the first (the flier) opposite to the other end of the bobbin and rotatable in unison with the flier, from which extremity in turn the yarn passes upon the second 35 guide to a point thereon at or near the rotational axis of the guide, from whence it passes finally to a take-off element for the twisted product, the 40 flier of the unit being driven by the said second yarn guide through the intermediary of the yarn. The yarn thus forms a loop in its passage from the bobbin to the take-off element and in said 45 passage has imparted to it two twists per revolution of the yarn guide and flier. Twisting units involving the above principle of operation, therefore, will be hereinafter referred to as twisting units of the "loop" type.

According to the present invention, a twisting 50 unit of the class specified comprises a plurality of individual sub-units of the loop type incorporated together in multiple relation in a single composite unit, in which the sub-units are disposed parallel to one another, the bobbins of the 55 sub-units being stationary therein and the sub-

units mounted upon a stationary carrier common to them all and accommodated with the sub-units between a positively driven primary yarn guide disposed opposite to the assemblage of sub-units at one end thereof with its axis parallel 60 to the rotational axes of these units and a primary rotary flier disposed co-axially with the primary yarn guide opposite the said assemblage of sub-units at the other end thereof, the multiple-twisted yarns from the sub-units being led 65 on to the primary flier at a point thereon near the rotational axis thereof, and from the outer extremity of this flier, ballooning around the assemblage of sub-units, to the radially outer extremity of the primary yarn guide, thence to a 70 point on this guide near the rotational axis thereof and finally on to a take-off element for the doubled and twisted product.

According to a preferred arrangement, the 75 stationary feed bobbins or the like are conical-ended with the end of narrower diameter disposed towards the leading-on point for the yarn on the flier. Thus, it is found, with this form of feed bobbin or the like, that the yarn more readily pays off from the stationary bobbin to 80 said leading-on point than from a parallel-sided reel, with consequent lessening of strain on the unit.

It is also preferred that the various parts set 85 forth above comprising the improved twisting unit of the invention shall be constructed in an overhung form in which the bobbins, the fliers and the yarn guides of the sub-units are all supported from one end only of the sub-unit and the assemblage of sub-units, the primary flier and 90 the primary yarn guide are also all supported from one end only of the composite unit.

The invention will now be further described with reference to the accompanying drawing, 95 which illustrates a preferred embodiment by way of example, and in which,

Figure 1 is a central longitudinal section through the composite twisting unit according to the invention, and

Figure 2 is a transverse section through the 100 unit on the section line 2—2 of Figure 1.

Like reference characters indicate like parts in the two figures.

The composite unit shown comprises three 105 sub-units mounted as a collective assemblage upon an overhung shaft 1, itself supported upon bearings 2 and belt driven through the intermediary of a pulley 3 fast upon the shaft.

Each sub-unit consists of a stationary bobbin 110 carrier 4 mounted, through the intermediary of

an anti-friction rotational bearing, upon a rotatable spindle 5, the carrier 4 being adapted to receive upon it a conical bobbin, cop or cheese 6 which is stationary with the carrier. Adjacent 5 the base end of the cheese 6, is a circular dish 7 fast upon spindle 5 and therefore rotatable with it, and a double-ended arm 8 rotatably mounted in a bearing 9, the axis of which is coincident with that of spindle 5, the bearing 9 being incorporated 10 in the outer extremity of a U-shaped bracket 10 swingably hanging at its inner end, along with the bobbin carrier 4, with which it is fast, from the spindle 5. The bracket 10 is weighted with a counterpoise weight 11 which 15 operates yieldingly to control the bracket always to the lowermost position shown and at the same time to hold the bobbin carrier 4 and the cheese 6 thereon against rotation in the unit.

The dish 7 and arm 8 constitute yarn guides, 20 and the guide 8 is arranged to be rotated in unison with guide 7 by the pull of the yarn between the two guides, and with this in view the guide 8 is, as shown, of very light proportions.

Each sub-unit comprises, moreover, the usual 25 tensioner 12 for the yarn and guide ring 13. It may also include any of the usual self-stopping devices. Such are not shown.

The several spindles 5 of the assemblage of 30 sub-units are rotationally mounted in a triangular hollow carrier 14, which, in turn, is mounted upon one end of a sleeve 15 surrounding the overhanging portion of driving shaft 1 and, in turn, mounted thereon through the intermediary of anti-friction bearings 16, 17 at the two ends 35 respectively of the sleeve. This sleeve 15 is weighted against rotation upon shaft 1 by a counterpoise weight 18 depending from the inner end of the sleeve, the magnitude of this weight being such as to retain the whole assemblage 40 of sub-units upon the shaft 1 yieldingly against rotation thereon.

The spindles 5 of the sub-units are drivingly 45 connected with the shaft 1 through the intermediary of pinions 19, fast upon the spindles 5 and intermeshing with a central toothed wheel 20 fast upon the outer extremity of the shaft 1.

The composite unit further comprises a circular dish 21 fast upon the shaft so as to be rotatable with it, and a double-ended arm 22 50 rotatably mounted upon a bearing 23 carried upon a bracket 24 affixed to the carrier 14. The dish 21 and arm 22 constitute, as in the case of the dish 7 and arm 8 of the sub-units, yarn guides and the guide 22 is arranged to be rotated by the dish 21 through the pull of the 55 yarn extending between the two guides.

The guides 8 of the sub-units are formed at the ends with eyes 25 through either of which the yarn may be threaded, and each dish 7 is 60 formed with an entry passage 26 for the yarn, this passage being situated at the periphery of the dish and being of such a form as to guide the yarn with the least degree of obstruction to its movement relatively to the dish, and an issue 65 passage 27 extending radially of the dish through the central boss thereof and leading to an axial passage 28 provided for the yarn through the spindle 5.

Similarly, the arm 22 is formed with an eye 70 29 at each end and the dish 21 has in its periphery a diametrically opposed pair of entry passages 30 for the yarn and extending radially through its central boss an issue passage 31 for the yarn, said issue passage communicating with an axial 75 passage 32 for the yarn in the shaft 1,

The yarn from the cheese 6 of each sub-unit is fed to the flier 8 of the sub-unit via the tensioner 12, from which the yarn passes through an axial passage in the bearing 9, then radially outward to the eye 25, then back to the entry passage 26 of guide 7, from thence inwardly to the issue passage 27, along the axial passage 28 in spindle 5, thence to a doubling eye 33 and tensioner 34 (both of these elements being supported on the aforesaid bracket 24), from the tensioner 34 through an axial passage in bearing 23, from the outlet end of this passage through an eye 35 formed in guide 22 through eye 29 of said guide, across to eye 30 of guide 21, inwardly through issue passage 31 of said guide 19, along axial passage 32 of shaft 1 and finally on to a take-off roller 36.

As will be appreciated, with this arrangement, the yarn passing between the guides 7, 8 of the sub-units and guides 21, 22, balloons out as shown, and in order to prevent the ballooning yarn on the sub-units from conflicting with that ballooning between the yarn guides 22, 21, each sub-unit comprises, in addition to the parts already enumerated, a circular guard ring 37 mounted upon the bracket 10, and the yarn passing between the sub-unit guides 7, 8 balloons between this ring 37 and a larger ring 38 completely encircling the assemblage of sub-units and intervening between the ballooning yarn on the 105 sub-units and that passing between the yarn guides 22, 21, the said ring 38 being mounted upon an arm 39 projecting axially of the unit from the lower end of the counterpoise weight 18.

In the actual form of the improved twisting 110 unit shown, the gear ratio of the pinions 19 to the central toothed wheel 20 is 1:2, and consequently, for each revolution of the driving shaft 1, the spindles 5 rotate through two revolutions, and therefore, per revolution of said driving 115 shaft, the yarn from each bobbin of the composite unit receives four revolutions of twist from the time it leaves the bobbin to the time it reaches the doubling eye 33 and in the result each yarn receives six revolutions of twist per 120 revolution of the driving shaft between the bobbin and the take-off element 36, four of these revolutions of twist being applied prior to doubling and two after.

Obviously, however, the gear ratio of the spindles 5 to the wheel 20 may be any other desired ratio than 1:2, with corresponding variation of the number of revolutions of twist applied to the individual yarns.

The improved construction of composite twisting 130 unit provided in accordance with this invention, more particularly the specific form of such construction described above with reference to the accompanying drawing, has been found to be highly meritorious both from the point of 135 view of ease of initial threading and facility of use generally and also from the standpoint of efficiency of operation, the twisted and doubled product producible with the improved unit being of highly uniform character and quality. 140 Moreover, the improved construction has been found to make for maximum avoidance of breakages both of the yarn in course of twisting and doubling in the unit and also of the rapidly rotating parts of the unit.

What I claim and desire to secure by Letters Patent of the United States is:—

1. In a twisting unit of the class specified, a plurality of individual sub-units of the loop type herein specified incorporated together in multiple 150

relation in a single composite unit, in which the sub-units are disposed parallel to one another, the bobbins of the sub-units being stationary therein and the sub-units mounted upon a stationary carrier common to them all and accommodated with the sub-units between a positively driven primary yarn guide disposed opposite to the assemblage of sub-units at one end thereof with its axis parallel to the rotational axes of these units and a primary rotary flier disposed co-axially with the primary yarn guide opposite the said assemblage of sub-units at the other end thereof, the multiple-twisted yarns from the sub-units being led on to the primary flier at a point thereon near the rotational axis thereof, and from the outer extremity of this flier, ballooning around the assemblage of sub-units, to the radially outer extremity of the primary yarn guide, thence to a point on this guide near the rotational axis thereof and finally on to a take-off element for the doubled and twisted product.

2. In a twisting unit of the class specified, the parts set forth in claim 1, in a form in which the bobbins are conical-ended with an end of narrower diameter disposed towards the leading-on point for the yarn on the flier.

3. In a twisting unit of the class specified, the parts set forth in claim 1, in an overhung form in which the bobbins, the fliers and the yarn guides of the loop type sub-units are all supported from one end only of the sub-unit and the assemblage of sub-units, the primary flier and the primary yarn guide are also all supported from one end only of the composite unit.

4. In a twisting unit of the class specified, the parts set forth in claim 1, in an overhung form in which the bobbins, the fliers and the yarn guides of the loop type sub-units are all supported from one end only of the sub-unit and the assemblage of sub-units, primary flier and the primary yarn guide are also all supported from one end only of the composite unit, the arrangement being such that the twisted and doubled product issues from the supported end of the composite unit.

5. In a twisting unit of the class specified, the parts set forth in claim 1, in an overhung form

in which the bobbins, the fliers and the yarn guides of the loop type sub-units are all supported from one end only of the sub-unit and the assemblage of sub-units, the primary flier and the primary yarn guide are also all supported from one end only of the composite unit, the arrangement being such that the twisted and doubled product issues from the supported end of the composite unit, and the fliers of the sub-units being rotationally mounted upon the outer end of a weighted U-shaped bracket accommodating the bobbin within its bend and freely mounted at its inner end upon a stationary carrier for the sub-units.

6. In a twisting unit of the class specified, the parts set forth in claim 1, in a form in which the several loop type sub-units and the stationary carrier are mounted through the intermediary of anti-friction rotational bearings upon an overhung driving shaft, the yarn guides of the sub-units being mounted upon spindles which are supported in bearings in the carrier and are drivingly connected to the said shaft through the intermediary of a toothed wheel fast on the extremity of said shaft and in mesh with pinions 100 on the spindles.

7. In a twisting unit of the class specified, the parts set forth in claim 1, in an overhung form in which the bobbins, the fliers and the yarn guide of the loop type sub-units are all supported from one end only of the sub-unit, and the assemblage of sub-units, the primary flier and the primary yarn guide are also all supported from one end only of the composite unit, the fliers of the sub-units are rotationally mounted upon the outer end of 105 a weighted U-shaped bracket accommodating the bobbin within its bend and freely mounted at the other end upon a spindle which is rotational in bearings in the stationary carrier, the said carrier is mounted through the intermediary of 110 anti-friction bearings upon an overhung driving shaft and is weighted to hang stationary thereon and said shaft is drivingly connected to the spindle of the sub-units through the intermediary of 115 a toothed wheel fast on the extremity of the shaft 120 and in mesh with pinions on the spindles.
